JAMES NISBET, OF PAWTUCKET, RHODE ISLAND, ASSIGNOR TO ISAAC GILL, TRUSTEE,
OF PAWTUCKET, RHODE ISLAND.

APPARATUS FOR CLEANING OUT SEWER CATCH-BASINS.

1,316,851.

Specification of Letters Patent. Patented Sept. 23, 1919.

Application filed November 17, 1915. Serial No. 62,046.

To all whom it may concern:

Be it known that I, JAMES NISBET, a citizen of the United States, residing at Pawtucket, in the county of Providence, State 5 of Rhode Island, have invented a certain new and useful Improvement in Apparatus for Cleaning Out Sewer Catch-Basins, of which the following is a specification, reference being had therein to the accompanying drawings.

The invention provides a practical apparatus for expeditiously and economically cleaning out sewer catch-basins, it comprising portable cleaning-out mechanism including power-driven mechanism all mounted upon a self-propelling vehicle-truck having a dumping body and adapted to travel under its own power from point to point, in order to take the apparatus to the catch 15 basin which it is desired to clean out, and afterward take the apparatus with the spoil to the required dumping ground. At the present time the work of removing accumulations of mud, sand, and various kinds 20 of debris, from sewer catch-basins is performed in actual practice by manual labor. As usually performed one laborer descends into a catch-basin which is to be cleaned and shovels the muck, sand and rubbish into 25 buckets which are lowered by hand into the catch-basin and when filled are hoisted by hand and emptied by hand into a cart or upon the adjacent roadway. The work is 30 unpleasant and unhealthful, since the laborer who descends into the catch-basin 35 has to stand in a bad-smelling unwholesome mass, the latter usually submerged under more or less filth-charged water, and more or less of the water, mud, and other con- 40 tents of the bucket that is being withdrawn from the catch-basin splashes or falls upon him. The work of shoveling the heavy wet 45 contents of the catch-basin is very laborious. Not only is the weight of the water- 50 changed successive shovelfuls considerable, but in addition the suction which has to be overcome in lifting each shovelful requires the exercise of considerable strength to overcome it. Sometimes, the mud or the like is 55 dug out and withdrawn by means of hoes or similar implements in the hands of a workman standing on the sidewalk above the catch-basin, which is a slow operation. Both of the modes of clearing out a catch- 60 basin which have just been referred to are

slow and expensive, and are inadequate in times of emergency, as when a storm washes unusual quantities of material into the catch-basins of a city or town. When this happens at present, the prompt cleaning out 60 of a system of catch-basins necessitates the employment of a large number of laborers and heavy expense. Unless a large force is set to work, the choked-up condition of some of the catch-basins continues for an indefinite period of time, with liability to 65 damage to roadways and property owing to the inability of surface water to escape through the catch-basin into the sewers in case of another rainfall.

The apparatus in which the invention resides, designed for the work of cleaning out sewer catch-basins, comprises a self-propelling vehicle, a dumping body or the like receptacle in connection with such vehicle designed to receive the spoil taken from a catch-basin, an orange-peel or the like dredging bucket of the required small size and proportions adapted to be passed through the manhole at the top of a catch-basin, means for lowering and raising the bucket by power at the will of the operator and enabling it to be swung about within the catch basin by an operator and caused to act at any desired point in the lower 80 part of the latter, means for closing and opening the bucket at the will of an operator, and a movable crane for enabling the bucket to be swung into position to enter the manhole or into a position over the 85 dumping body, and vice versa.

The drawings show an illustrative embodiment of my invention, which I will now describe.

Figure 1 of the drawings shows the apparatus aforesaid in perspective and represents it as standing alongside the manhole of a catch-basin.

Fig. 2 is a detail view showing the locking device for the crane to keep the latter from 100 swinging.

The self-propelling vehicle shown in the drawings comprises a truck mounted upon strong wheels 1, 1, having heavy and substantial tires 2, 2, of the character provided 105 for vehicles required to carry heavy loads, the engine being located within the hood 3 and the steering apparatus being shown at 4 conveniently adjacent the driver's seat 5. The rear part of the vehicle carries the 110

wagon-body 6, of proper construction to provide for dumping. Intermediate the driver's seat 5 and the dumping body 6 is located the power-equipment for working 5 the dredging bucket 7 and in this case also for operating the dumping-body. There is also located at this point a centrifugal pump 8 having pipes 9, 9^a, connected therewith and by means of which water contained in a 10 catch-basin may be withdrawn therefrom when required. The dredging bucket 7 shown in the drawings is of the orange-peel type and comprises four sections or segments. A single cable 7^a is shown connected therewith for the purpose of supporting, lowering, and raising the same. The said cable extends from the bucket up to a sheave or pulley 7^b upon the arm of a swinging crane 10 that is mounted upon the vehicle, 15 and after passing partly around the sheave or pulley 7^b passes to and partly around a second sheave or pulley 7^c, the latter located approximately in line with the upright shaft or mast 10^a of the crane, and from the 20 said pulley or sheave 7^c the said cable passes downward and finally is connected to the windlass located between the drivers' seat 5 and the body 6 and forming a part of the power mechanism. The gearing of such 25 windlass is shown in Fig. 1. The said windlass is arranged to be operated by power at the will of an operator in any of the usual modes so as to cause it to turn in order to wind up the cable to raise the bucket, or 30 unwind the cable to lower the bucket, or to remain at rest. The upright shaft or mast 10^a of the crane 10 is mounted suitably in bearings 10^b, 10^c, in connection with the vehicle and adjacent the body 6. Provisions of usual 35 character are supplied in connection with the bucket 7 for the purpose of automatically closing and opening the bucket at the will of the operator. In the present instance these provisions include hose-pipes 11, 11, leading 40 from the bucket to a hydraulic pressure apparatus, the controlling devices of which are indicated at 12. Thus in this instance the bucket itself is opened and closed by means of hydraulic pressure transmitted at 45 the will of the operator by means of oil contained within the hose-pipes 11, 11. A catch-basin manhole 13 is shown open or uncovered, and the apparatus is shown located alongside the curbing of the side-walk adjacent the said man-hole, with the 50 arm of the crane swung outboard and bucket 7 elevated above the man-hole. The bucket is of quite small dimensions such as to enable it in a closed state to pass down through the man-hole and to be withdrawn subsequently through the man-hole with the load it has taken up. After having been lowered in a closed condition through the man-hole by causing or permitting the hoist to pay 55 out cable, the bucket is caused to open, and

then is swung within the catch-basin by taking hold of the vertical portion of the cable into position to descend at the desired point within the catch-basin upon the contents of the latter, and then the valves of the 70 hydraulic pressure devices are operated to cause the bucket to close upon the portion of said contents which it has inclosed, after which the hoist is caused to operate to lift the bucket and its contents out of the man-hole, and then the bucket is raised high enough to permit it to be swung inboard over the body 6. It is thus swung and the pressure devices are operated to cause the bucket to open and discharge into the body. 75 The operation having been continued until the catch-basin is properly emptied, the apparatus is caused to travel under its own propelling power to the next catch-basin to be cleaned, or, when the body 6 is filled, to 80 the dumping ground, at which latter place the contents of the body 6 are dumped, and the vehicle is caused to run to the next catch-basin to be taken in hand.

It is intended that in the use of the apparatus at a catch-basin the boom of the crane shall be swung outward from the body 6 into an outstanding position in which its free extremity extends above the man-hole, so that the bucket in being lowered shall 90 descend vertically into and through the man-hole and subsequently in being raised shall rise vertically out through the man-hole. The outward movement of the boom into the desired position may be occasioned by one 95 of the workmen employed in connection with the apparatus, as for instance by the one who stands at the man-hole to manipulate the bucket, and who may for the purpose pull outward upon the hose-lengths 11, 11. 100 Or the crane may be hung in manner to cause it to tend to swing outward of itself. Usually, however, in the employment of the apparatus the wheels at the side of the truck nearer the man-hole are lower than those at 105 the other side, in consequence of the customary curvature or inclination of the roadway from the middle of its width toward either side, or in consequence of the said wheels resting in the depression or hollow of 110 the gutter. Consequently, the boom will tend to swing outward without special provision therefor. For the purpose of arresting the boom in proper position with reference to the man-hole, and so as to render unnecessary the intervention of one of the workmen for the purpose, I provide a checking chain or rope 15 which extends from some convenient point of attachment at the far side of the body to the boom, and is of 115 the proper adjusted length to arrest the outward movement of the boom when its end is in position over the man-hole. To provide for adjustment of the outward movement of the boom, the chain is engaged at different 120 125 130

points in its length with the boom, as by catching different links upon a hook or pin, as 16, provided in connection with the boom; or in practice any approved means of taking up the required portion of the length of the chain or letting out such portion may be adopted. This chain enables a workman occupying a position at the far side of the body 6 to pull the boom of the crane inward by 10 taking hold of the chain, and thus swing the upraised filled bucket into position to discharge at the required point within the body 6.

I make provision for locking the crane 15 from swinging during the movement of the apparatus from point to point. Thus I have shown at 17 a locking pin adapted to occupy holes in a flange or lug 18 at the foot of the mass or upright 10^a of the crane, and 20 in a suitable outstanding portion or flange 19 adjacent the lower bearing 10^c for the said mass or upright, shown best in Fig. 2. The holes in the members 18 and 19 are arranged to register with each other when the 25 crane has been given its idle position with the boom inward parallel with the body, and when they are in register the insertion of the pin will serve to lock the crane and its boom into position mentioned above. The

pin is attached by a short length of chain 20 30 to a convenient fixed part in connection with the truck, so as to keep it from getting out of the way or lost when not in use for locking purposes.

I claim as my invention:—

The herein described apparatus for use in 35 cleaning out sewer catch-basins comprising a self-propelling vehicle, having a dumping body to receive the spoil taken from a basin and subsequently discharged at the 40 dumping-ground, an orange-peel bucket of a size adapted to pass through a catch-basin man-hole, a movable crane from which the bucket is suspended, for enabling the bucket to be swung outboard and inboard at will, 45 means for lowering and raising the bucket by power at the will of an operator and by which it may be swung about within the catch-basin to land at the required point therein, and means for closing and opening 50 the bucket at the will of an operator.

In testimony whereof I affix my signature in presence of two witnesses.

JAMES NISBET.
